UNITED STATES PATENT OFFICE

TARIO YONEKURA, OF TAKAOKA, JAPAN

SUCTION DEVICE OF PAPER-MAKING MACHINES

Application filed July 26, 1928, Serial No. 295,563, and in Japan August 18, 1927.

This invention relates to an improvement in suction device for paper-making machines. According to this invention, the rolls are placed at the upper two extreme ends of the base of an inverted triangle, and a revolving suction pipe is placed at the apex of the said triangle. A suction chamber, with its two sides closed air-tight, is formed by a flexible belt running over the said rolls and a suction pipe, by means of which moisture in the wet paper is removed when said paper passes over the suction surface. An object of the present invention is to produce a paper having the same fineness or smoothness on both sides by means of wire cloth bearing against wet paper in the machine. A further object of this invention is to raise the efficiency of the device by providing two suction boxes for the purpose of removing simultaneously the moisture from both surfaces of the paper whereas, in the machines hitherto used, one suction box only is provided to absorb the moisture from the reverse surface of the paper, i. e. from the side of the paper in contact with the rolls. Another object of this invention is to draw off the moisture with a reduced vacuum in a suction box facing said reverse side of paper. Owing to this provision of two boxes for each paper surface instead of one as hitherto known, the suction power is doubled. In the drawings:

Fig. 1 shows the transverse section of the suction device;

Fig. 2 its plan view;

Fig. 3 a side view of the side wall partially cut away;

Fig. 4 the plan view showing the one side of the suction device;

Fig. 5 the sectional plan view of the side wall of Fig. 3 cut along the line V—V.

Fig. 6 the sectional plan view cut along the line VI—VI of Fig. 3;

Fig. 7 the sectional plan view of the same cut along the line VII—VII of Fig. 3; and

Fig. 8 to 18 the modified forms of the suction device in sketches.

To describe the device in details, to one end of the base of an inverted triangle, prime mover roll 1 and to the other end a follower roll 2 are fixed. The revolving axles 3 and 4

of the said rolls are connected by a chain belt 5. The suction chamber 9 is formed by an endless rubber belt 8 stretched or run over the prime mover roll 1, the perforated revolving suction pipe 7 provided at the apex or lowest point of the inverted triangle and the follower roll 2, and by closing the two sides of the chamber with wood or other materials to form the side walls 10. Through the side-walls, run two horizontal rods 14 and 15 to which are fitted upright poles 12 and 13 standing on the frame 11. Two horizontal rods 14 and 15 are screwed on two outer pipe rods 16, which are fitted to the side walls and to which a handle 17 is fitted. By turning the handle, the outer pipe rods are made to advance toward or recede from the side-walls so as to correspond to the motion of the rubber belt 8. A stuffing box 18 is provided for at the outer ends of the protecting pipe rods in order to make them air-tight. An adjusting rod 19 is fitted to the side-walls and another stuffing box 20 is arranged at the parts of the walls through which said rod runs to keep them air-tight.

The bent end of a level plate is fixed to the inner end of the adjusting rod at a point close to the upper ends of the side-walls and also close to the sides of the rubber belt. By these means the level plate is made to reciprocate on a level by the manipulation of the adjusting rod so that the area of suction is adjusted to any degree desired.

Inside the above mentioned suction pipe 7 a brushing rod 22 is axially arranged, said pipe being kept air-tight by a stuffing box 23. These means are used for brushing and cleaning the suction pipe provided with perforations 24 from the inside. Another stuffing box 25 keeps the part of the suction pipe 7 carrying the brushing rod 22 air-tight. A pipe 26 is connected with the suction pump by means of which moisture of the wet paper is absorbed when it passes the suction surface, the remainder being removed in the suction chamber.

In the above manner, the wet paper 30 lying in front of the couch roll is made to stick close to the reverse surface of the straining wire net 31 (Fig. 8) which carries the

paper forward. The width of the suction surface is adjusted by means of level plates regulated by the adjusting rod. The next step is to make the side-walls of the suction chamber airtight, this being done by turning the handle 17 and thereby closely fitting the side-walls of the suction chamber to the sides of the rubber belt 8. Then, the prime-mover roll 1 is revolved together with the follower-rolls 2, its speed being kept equal to that of the wet paper 30, passing the suction surface of the suction chamber 9. The interior of said chamber is evacuated by the action of suction pump.

Fig. 8 shows by way of example a suction roll arranged under a cloth or strainer wire-cloth. The suction chamber 9 is formed by a rubber belt 8 stretched over the prime mover roll 1 by the perforated revolving suction pipe 7, and the follower-roll 2. The moisture of the wet paper 30 is absorbed by said suction chamber 9 when the paper on the cloth or strainer wire-cloth passes the suction surface of said chamber. Tension of the rubber belt may be regulated by means of a stretcher roll 6. In Fig. 9 the strainer wire-cloth is so positioned as to pass over the suction surface. This is done by stretching the wire-cloth 32 over the prime-mover roll 1, follower-roll 2, and stretcher roll 6. Fig. 10 is another modification of the device 5.

According to Figs. 11 and 12 the suction chamber 9 is placed over the strainer wire-cloth or cloth of a paper-making machine of long net type. In this case the moisture is absorbed directly off the wet paper, which is then carried forward and pressed. For this purpose a suction chamber 9, stretcher-rolls 6 and shower-rolls 29 are provided and an endless wire-cloth 32 is stretched over a guide-roll 33, the stretcher roll 6, the follower-roll 2 and the prime mover roll 7. Said wire cloth can be led through a water tank 34 and it is then washed once in each revolution.

Fig. 13 shows a suction roll which is so made as to absorb the moisture directly from the wet paper by means of a suction chamber which is placed in contact with the surface of wet paper passing the surface of cylinder mould. The device is operated in such a way that the prime-mover roll 1 turns the follower-rolls 2 by means of which the wet paper is carried forward together with wire cloth 32 which is stretched over the prime-mover roll 1, follower roll 2, stretcher roll 6 and guide roll 33.

Fig. 14 shows a suction roll arranged inside of the cylinder mould. In this case, the moisture contained in the wet paper passing the surface of the cylinder mould is absorbed into the suction chamber 9 formed by the rubber belt 8 stretched over the prime-mover roll 1, follower-roll 2 and suction pipe 7,

the tension of the belt being regulated by the stretcher roll 6.

Fig. 15 is a somewhat modified construction of the device shown in Fig. 14.

Figs. 16 to 18 show other modified forms of the device according to this invention.

In all modifications prime-mover roll and follower-roll are connected by a chain belt and suction pipe 7, the prime-mover roll being connected with a shaft. However, if some of the above elements will be removed or disconnected the endless belt will, automatically, move or revolve at a speed equal to that of the strainer wire-cloth 32 owing to its friction with the belt created by the suction force.

Claims:

1. In a suction device for paper-making machines, the combination of a prime-mover roll at one end of the machine, a follower roll at the other end thereof, a suction pipe between said rolls, a flexible belt extending around said rolls and suction pipe to form a chamber having a suction surface, and side-walls for said chamber combining with said belt to make the chamber airtight.

2. In a suction device for paper-making machines, the combination of a prime-mover roll at one end of the machine, a follower roll at the other end thereof, a suction pipe between said rolls, a flexible belt extending around said rolls and suction pipe to form a chamber having a suction surface, side-walls for said chamber combining with said belt to make the chamber airtight, and a wire cloth extending over the suction surface of said chamber.

3. In a suction device for paper-making machines, the combination with a cylinder mould; of a prime-mover roll at one end of the machine, a follower roll at the other end thereof, a suction pipe between said rolls, a flexible belt extending around said rolls and suction pipe to form a suction chamber, said belt being positioned close to the inner face of said cylinder mould to absorb the moisture off the wet paper when it passes the surface of said mould, and side walls for said suction chamber.

In testimony whereof I have affixed my signature.

TARIO YONEKURA.
